[57] CLAIM

The ornamental design of grill branding irons, as shown
and described.

DESCRIPTION

FIG. 1 is a perspective view taken from the front and
left side of the grill branding iron showing my new
design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a perspective view taken from the front and
left side of a second embodiment of the grill branding
iron shown in FIG. 1;

FIG. 8 is a front elevational view of FIG. 7;

FIG. 9 is a rear elevational view of FIG. 7;

FIG. 10 is a top plan view of FIG. 7;

FIG. 11 is a bottom plan view of FIG. 7;

FIG. 12 is a right side elevational view thereof, the left
side being a mirror image of the right side shown;

FIG. 13 is a perspective view taken from the front and
left side of a third embodiment of the grill branding iron
shown in FIG. 1;

FIG. 14 is a front elevational view of FIG. 13;

FIG. 15 is a rear elevational view of FIG. 13;

FIG. 16 is a top plan view of FIG. 13;

FIG. 17 is a bottom plan view of FIG. 13; and

FIG. 18 is a right side elevational view thereof, the left
side being a mirror image of the right side shown.

The centers of FIGS. 4-6, 10-12, and 16-18 are broken
away for the convenience of illustration only.
